(63) Continuation-in-part of application No. 29/570,437, filed on Jul. 8, 2016, and a continuation-in-part of application No. 29/578,841, filed on Sep. 26, 2016, and a continuation-in-part of application No. 29/592,022, filed on Jan. 26, 2017, which is a continuation-in-part of application No. 29/570,437, application No. 29/600,776, which is a continuation-in-part of application No. 29/580,507, filed on Oct. 10, 2016.

CLAIM

The ornamental design for a display screen or portion thereof with keyboard graphical user interface, as shown and described.

DESCRIPTION

FIG. 1 is a front view of a first embodiment of a display screen or portion thereof with a keyboard graphical user interface showing my new design; and, FIG. 2 is a front view of a second embodiment thereof. The broken line showing of a display screen with graphical user interface is included for the purpose of showing portions of the article which form no part of the claim.
